UNITED STATES PATENT OFFICE.

JOHN KIEWICZ, OF HYDE PARK, MASSACHUSETTS, ASSIGNOR TO THE REECE BUTTON HOLE MACHINE COMPANY, OF BOSTON, MASSACHUSETTS, A CORPORATION OF MAINE.

BUTTONHOLE-STITCHING MACHINE.

1,188,945.

Specification of Letters Patent. Patented June 27, 1916.

Original application filed March 26, 1914, Serial No. 827,276. Divided and this application filed August 26, 1915. Serial No. 47,405.

To all whom it may concern:

Be it known that I, JOHN KIEWICZ, a citizen of the United States, residing at Hyde Park, in the county of Suffolk and State of Massachusetts, have invented certain new and useful Improvements in Buttonhole-Stitching Machines, of which the following is a specification, reference being had therein to the accompanying drawing.

10 This invention relates to buttonhole stitching machines, particularly of that type wherein a frame carrying the stitch forming mechanism on the one hand and a work support or clamp on the other hand are relatively movable, so as to enable the stitching to be carried along the sides of the buttonhole and around its end or ends.

15 The general object of the present invention is by reorganization of structure and mode 20 of operation to generally improve the running qualities and efficiency of buttonhole stitching machines and to permit increase of speed of operation without introducing objectionable shock, vibration or noise.

25 Other objects hereof will be made apparent during the hereinafter following description of the nature of the invention.

30 This application is a division of my prior application Serial No. 827,276, filed March 26th, 1914.

35 First will be described one form in which the present improvements may be carried out and afterward the novel features will be particularly pointed out in the appended claims.

40 In the accompanying three sheets of drawings forming a part hereof, Figure 1 is a left elevation of a buttonhole stitching machine with its base and legs omitted, embodying the present invention. In this and the other figures the parts are shown in that stage of 45 operation where the work clamp has automatically opened, but before the same has shifted completely rearwardly to cutting position. Fig. 2 shows at the left in top view and at the right in rear view the type of buttonhole adapted to be made on the specifically illustrated machine hereof. Fig. 3 is a bottom plan view of the mechanism 50 shown in Fig. 1. The side nearest the observer in this figure will be referred to as the right-hand side of the machine. Fig. 4 is a left elevation partly in section of the cutter, anvil and under-stitching mechanism,

the latter being shown shifted for convenience to a position facing the observer. Fig. 5 is a plan view of the under stitching mechanism and certain other parts beneath the table.

55 The invention is shown applied to a species of machine in which, briefly stated, the operation may be substantially as follows: In the initial position the work clamp is open, the cutter and anvil are retracted and both needles are out of the work. The operator positions the work beneath the clamp and presses the hand lever for starting the mechanism. This operation throws into action the primary or what may be termed the quick feed clutch, in a manner similar to the action described in prior Patent No. 1,030,589. This quickly rotates the feed shaft which, through the main cam, effects first the closing of the clamp upon the work, where it becomes locked, the forward swinging of the anvil and the operation of the cutter to cut the buttonhole, the separation and retraction of the cutter and anvil, followed by a quick forward movement (e. g. three-fourths inch) of the clamp plate or work support from cutting position to the position where stitching commences, during which forward movement the work is stretched to spread the buttonhole slit. At this point the main cam, acting through the shipper lever, throws the quick feed clutch automatically out of action, and throws the stitching clutch and shaft into action. The stitch shaft, while operating the needles, also effects through the feed shaft and main cam a slow step-by-step feed of the work. During the feed movement around the buttonhole the clamp moves forwardly along one edge and back along the other edge of the buttonhole. At the ends the clamp has a lateral movement and during such lateral movement the entire stitching mechanism revolves about its vertical axis so that the stitches are properly laid around the margin of the buttonhole slit, as seen in Fig. 2. At the completion of the stitching, the main cam automatically operates the stitch clutch to stop the shaft, and thereupon the quick feed clutch is again thrown into action by the shipper lever to shift the clamp plate quickly rearwardly to initial or cutting position. At the beginning of this quick rearward movement the clamp is automatically

sprung open, permitting the removal of the work. It is in this stage in the cycle of operations that the parts are illustrated in the drawings hereof. The work clamp continues its rearward movement, at the end of which the quick feed clutch is thrown out of action, and the entire machine comes to a stop with the cutter elevated, the needles out of the work and the clamp open, as at the beginning, ready for the re-positioning of the work and the operation of the hand lever, which has meanwhile sprung upward.

Referring specifically to the different elements of the illustrated structure, the bed plate 20 may be swingingly attached to a base 21 indicated in dotted lines, Fig. 1. The bed plate supports the head 22, which, by its foot 23, is secured fast to the bed plate, and has an overhanging arm 24 supporting the upper needle fittings. Beneath the bed plate 20 is a cam casing 25 inclosing the large circular main cam 26. This main cam affords the general control of the machine, and itself is adapted to rotate first rapidly, then slowly, then rapidly, during the formation of each buttonhole, and the main cam has peripheral teeth for the purpose of such slow rotation. The main cam 26 contains a number of cam grooves or surfaces 27 for the various purposes of the machine, for example, at the upper surface of the cam disk 26 is provided near the center with the cutter operating cam 26^a. One of the cam surfaces at the underside of the disk near its periphery is the cam 26^b, which effects the closing of the work clamp upon the work, and also serves to swing the anvil to operative position beneath the cutter. Generally this main cam 26 is a well-known element in this type of machine, but its different portions effect novel operations, as will hereinafter appear. Another important member of the operating mechanism is the so-called shipper lever 28, corresponding generally with the three-armed lever a^9 of said prior patent. The shipper lever does not particularly concern the present invention, and will be further referred to only incidentally.

The work clamping mechanism shown at the forward upper side of the bed plate will not be described in detail. It includes a clamp plate 30, and above it a pair of clamp members 32, 32. These are carried by a clamp operating mechanism, which is described in detail in my aforesaid prior application. One of the controlling parts of this mechanism is the rock shaft 40, which is adapted to be swung for the purpose of closing the clamp plates, which thereupon become locked. The oscillation of the rock shaft is effected through a forwardly extending arm 43 thereon, which may be pulled downwardly at the proper time from the main cam, in order to close the clamp upon

the work. When the clamp is closed, it is automatically locked by pivoted lock 45. The rock shaft 40 may also be swung by means of a hand lever 44. For the automatic closing of the clamp, the lever 43 upon the rock shaft 40 has an offset crank-like portion, co-operating with which is a hook 47 whose shank extends downwardly to where at its lower end it is pivoted to the forward end of the clamp-closing cam lever 48 (Fig. 75 1). A spring 49 tends to hold the hook 47 forwardly in the position shown, while a spring 50 tends to sustain the forward end of the cam lever 48 against the tendency of the cam 26^a, acting upon the roller 51 carried by the lever 48, to depress the latter.

By the described arrangement the action of the clamp closing cam is to depress the cam lever, thereby pulling down the hook which rotates the rock shaft 40, depressing the upper clamp members and closing the clamp, which becomes locked by the device, 45, until released by other means.

The various connections for releasing the clamp, for moving it between the cutting and stitching positions, and for feeding it during the stitching, need not be described.

We come now to the cutter and anvil devices, more particularly involved in the present invention. The cutter is at the forward end of an arm 81 (see Fig. 1) fulcrumed near its middle and having a contact tongue 82 at its rear extremity resting upon the cam groove 26^a near the center of the upper side of the main cam whereby the cam effects the cutter operations in opposition to a suitable spring. Opposed to the cutter, below the clamp plate, is the anvil 86 consisting of a removable piece supported at the extremity of the anvil arm 87 (see Figs. 1 and 4). The anvil arm is shiftable, rendering the anvil capable of advancing to cutting position and, after cutting, withdrawing to the position shown in full lines in Fig. 4. The anvil arm is a solid member capable of receiving a heavy blow by the cutter and is so shaped in the irregular manner shown as to permit the fulcrum 88 at the arm's lower end to be located, as shown, in substantially direct alignment with the blow of the cutter so as to give the greatest solidity of resistance and avoidance of tendency to deflection. A spring 89 coiled around the fulcrum 88 tends to retract the anvil from cutting position. The anvil carrier 87 may be described as recessed at 90 at its forward side, the recess accommodating portions of the under stitching mechanism while the latter is idle and the anvil is operative. In this effective way the cutting position is enabled to be located in close proximity to the stitching position so that the amount of quick feed between cutting and stitching positions is materially reduced, not only obviating the

mechanical disadvantages of a more extensive jump of the work carried in the clamp plate, but causing a substantial saving of time, at the same time securing simplicity, 5 solidity and effectiveness of mechanism and operation. The described arrangement secures the advantages that would be had by a fixed anvil on the clamp plate, but obviates the very practical disadvantage that 10 such fixed anvil would necessarily be too light and therefore incapable of performing its work.

Hereinafter another advantage in the described arrangement will appear in that the 5 withdrawal of the anvil during stitching permits the under stitching mechanism to be designed, as shown, with a curved under needle oscillating about a simple pivot located substantially as high as the clamp 10 plate permits. Without the withdrawal of the anvil, as is clear in Fig. 4, there would be conflict between the anvil and the under needle pivot upon bodily rotating the under mechanism, as is necessary. The movement 15 of the anvil and carrier may be effected through an extension 93 formed on the clamp closing cam lever 48, so that the movement of the lever to close the clamp simultaneously shifts the anvil into position beneath the descending cutter. As seen in Fig. 1, 20 the extension 93 is held up by a spring 94 extending downwardly from the cam lever 48. The cam lever 48 is caused to descend a considerable distance in closing the clamp, 25 and in such descent it carries the extension 93 with it, the extension thereby striking the contact arm 95, which, being depressed, rocks the shaft 96 so as to swing forwardly the rocker arm 97, which, as indicated in 30 dotted lines in Fig. 4, presses the anvil carrier into operating position.

Some further general parts of the mechanism may now be conveniently referred to. A starting lever 100 is properly connected, 15 so that when depressed by the finger, it effects the commencement of operations by the throwing in of the clutch. The stitching mechanism comprises a curved under needle 123 and a straight upper needle 125, supported on a vertically reciprocating carrier 124. The under stitching mechanism is carried upon a stock 126, which oscillates about a vertical axis. This has a bearing ring 127 at its upper part, and a bearing 128 at its 20 lower part engaged by a surrounding bearing 130. The oscillation of the under stitching mechanism is accompanied by an oscillation of the upper needle carrier by means of upper and lower pinions 131 engaged by 25 upper and lower segment rocks 132, both of which are carried on a vertical shaft 133. This shaft has a rock arm 134 connected by a link 135, with a cam lever 136, which is 30 swung by the main cam. Carried by the stock 126 is a throat plate 144. Coöoperating

with the under needle is a looper 145. The under needle and looper are actuated by a vertically vibrating rod 149, which is connected by a lever 170 and eccentric rod 172 to an eccentric on the stitching shaft 214. 70

It will thus be seen that I have described a buttonhole machine attaining the objects and advantages and embodying the novel principles of the present invention. Since many matters of design, detail and other features may be variously modified without departing from the main principles hereof, no limitation to such features is intended excepting so far as set forth in the appended claims. 80

What is claimed is:

1. A buttonhole stitching machine including in combination a work clamp, an under stitching mechanism beneath the clamp, a buttonhole cutter above the clamp fitted to descend and rise, a cutter anvil, comprising a heavy rigid solidly mounted arm, having a stationary pivot a substantial distance beneath the clamp in line with the cutting movement, the same arranged to swing about said pivot relatively to the under stitching mechanism to and from cutting position, and connections for automatically actuating the anvil and cutter dissimultaneously with the stitching. 90

2. A buttonhole stitching machine including in combination a frame, stitching mechanism carried by said frame, a work clamp, means to lock the clamp when closed, a cutter above the clamp fitted to descend and rise, and a shiftable anvil beneath the clamp fitted and actuated to automatically advance to cutting position before the cutter's operation and to resume retracted position after cutting and before stitching, and a cam-operated lever adapted to both close the clamp and actuate said anvil. 100

3. A buttonhole stitching machine including in combination a work clamp, an under stitching mechanism beneath the clamp, a buttonhole cutter above the clamp fitted to descend and rise, a cutter anvil comprising a rigid arm shaped with a recess to embrace the under stitching mechanism during cutting and having a stationary pivot a substantial distance beneath the clamp in line with the cutting movement, the same arranged to swing about said pivot relatively to the under stitching mechanism to and from cutting position, and connections for automatically actuating the anvil and cutter dissimultaneously with the stitching. 110

4. A buttonhole stitching machine including in combination a work clamp, an under stitching mechanism beneath the clamp, adapted to bodily rotate during stitching about a vertical axis and comprising a needle fitted by a simple elevated pivot to swing above and below the work, a buttonhole cutter above the clamp fitted to descend and 120 125 130

rise, a cutter anvil comprising a heavy solidly mounted arm shaped with a recess to embrace the under stitching mechanism during cutting and having a pivot a substantial distance beneath the clamp in line with the cutting movement, the same arranged to swing about said pivot relatively to the under stitching mechanism to and from cutting position, and connections for automati-

cally actuating the anvil and cutter dis- 1 simultaneously with the stitching.

In testimony whereof, I have affixed my signature in presence of two witnesses.

JOHN KIEWICZ.
